CARLYLE H. SCOTT, OF NEW YORK, N. Y.

CONCRETE MIXER

Application filed December 3, 1928. Serial No. 323,387.

This invention relates to concrete mixers, and particularly to an improved mixer permanently mounted on a truck so that it will act both in the capacity of a mixer and a 5 transporting tank.

Another object of the invention is to provide in a concrete mixer a mixing structure which, when operated in one direction, will mix the sand, cement and other parts of the 10 conglomerate and when in another position will propel the mixed concrete to a discharge point.

An additional object is to provide in a concrete mixer means for first mixing the concrete 15 conglomerate and then mixing water therewith immediately before discharge of the batch.

Another object is to provide a concrete mixer permanently mounted on a truck with means for mixing the concrete while the 20 truck is standing still or moving with means for utilizing the exhaust from the engine of the truck to maintain the batch warm during a mixing operation.

In the accompanying drawings,—

25 Figure 1 is a side view of a concrete mixer disclosing an embodiment of the invention, certain parts being broken away;

Figure 2 is an end view of the structure shown in Figure 1;

30 Figure 3 is a longitudinal vertical sectional view through one of the discharge ports or outlets of the mixer shown in Figure 1;

Figure 4 is a sectional view through Figure 3 on the line 4—4;

35 Figure 5 is a longitudinal vertical sectional view through part of the mixer shown in Figure 1, the same being on a somewhat enlarged scale;

Figure 6 is a detail fragmentary sectional 40 view through Figure 5 approximately on the line 6—6, certain parts being broken away with the remaining part showing the mixing and propelling mechanism;

Figure 7 is an enlarged top plan view of 45 the inlet opening shown in Figure 1;

Figure 8 is a sectional view through Figure 7 on the line 8—8.

50 Referring to the accompanying drawings by numerals, 1 indicates a tubular tank which is preferably provided with an end 2 riveted

or integrally formed with the body of the tank. The end 3 opposite end 2 is preferably removable, though this is not absolutely essential. By making the end 3 removable the rotating parts shown particularly in Figures 5 and 6 may be readily applied or removed or may be readily adjusted or repaired at any time. The tank 1 is adapted to be substantially permanently mounted on a truck of any desired kind and preferably the exhaust 55 from the truck is connected with pipe 4, said pipe 4 discharging into the chamber 5 which is formed beneath tank 1 by reason of the casing or apron 6. Suitable openings are provided for chamber 5 so that the exhaust 60 discharged therein may escape but before escaping causes the parts to become heated, whereby concrete may be properly mixed even in very cold weather. The truck carrying the tank 1 may be any desired kind of a 65 truck provided with an internal combustion engine. Also, in trucks as now made there is provided a power take-off mechanism which may be reversed. To the power take-off 70 mechanism of the truck is applied a chain 7 adapted to be driven thereby so that the chain 75 may drive a sprocket 8 rigidly secured to the shaft 9. In this way the shaft 9 may be rotated or allowed to remain stationary while the truck is traveling or while the truck is 80 standing still. Connected with the shaft 9 is a spiral structure 10 which, when shaft 9 is rotated in one direction, will act as a mixing or stirring device and when the shaft is 85 rotated in the opposite direction will act as a screw or propelling device for forcing the batch out through the discharge outlet 11. If preferred, the batch could be discharged 90 out through the outlet 12. The outlets 11 and 12 are identical and are each provided with a flange 13, whereby they may be connected to a pipe, chute or other means for directing the batch to a desired point. A suitable knife valve 14 is provided, said valve 95 being pivotally mounted at 15 and having a hand hold 16, whereby the valve may be readily opened and closed. Referring again to shaft 9 it will be noted from Figures 1 and 5 that the same is supported by suitable bearings 17 and 18 at the respective ends of 100

the tank 1. This tank at the upper part is provided with an inlet member 19 designed to permit the insertion of matter to be mixed when open. The inlet 19 consists principally of an upstanding flange 20 secured to or formed integral with the tank 1 and is provided with a U-shaped channel portion 21 accommodating the sliding valve 22. This valve is provided with a hand hold 24 whereby the valve may be slid back and forth to an open and closed position. When mixing concrete the cement, sand and other matter is discharged through the inlet 19 until the required amount of each ingredient has been provided.

At any desired time the mixing device 10 is set into operation and the various materials are thoroughly mixed. After this has been done the mixture is left in place and transported in the tank 1 to the place where it is to be used. A short time before the mixture is to be used water is discharged from one of the tanks 26 and then the mixing structure 10 operated for a desired time until the water has been thoroughly brought into contact with the mixture. The mixing device 10 is then reversed, and in reversing the same it automatically becomes a screw, so that the mixed batch is then forced out through one of the outlets 11 and 12, the valve or gate 14 being open for this purpose. By this method the concrete is mixed during the time it is transported from the yard to the place where it is to be used. Also, it will be noted that the water is admitted only a short time before the batch is to be discharged so that the batch will not be cooked or undesirably acted on by the water. It will be noted from Figure 2 that the tanks 25 and 26 are connected to the tank 1 so as to discharge therein through pipes 27 and 28 and these pipes in turn are controlled by the valves 29 and 30. Preferably the water from one tank is sufficient to provide the desired moisture for the batch in tank 1, and after this batch has been discharged the water from the other tank is discharged into the tank 1, the outlets being closed. The stirring device 10 is then operated, whereby the parts are washed and after the washing operation the water and other matter are forced out of one of the outlets. The mixing device 10 as heretofore mentioned acts to mix the batch both when dry and when wet, and in addition, acts as means for propelling or forcing the batch out through one of the discharge outlets. In order to accomplish this the mixing device 10 comprises a screw 31, a shaft 32 and gates 33. The gates 33 automatically move to a closed position when the device is acting as a screw for forcing the batch out through one of the outlets. When the shaft 32 is reversed the various gates 33 automatically open and then the device acts as a stirring structure for stirring and mixing the batch while in a dry

state and also after the same has been supplied with liquid. The screw 31 is rigidly secured in any desired manner to shaft 32 so as to rotate therewith. Each of the gates 33 is provided with a door section 34 and a shaft 35. The shaft 35 is rigidly secured to shaft 32 and extends radially therefrom. Looped members 36 and 37 are rigidly secured to the door section 34 and loosely fit over shaft 35. This shaft is slightly larger at the inner end so as to provide a shoulder on which the looped members 36 may rest. From Figure 5 it will be noted that the door sections 34 slightly overlap certain parts of the screw 31 when the gates are closed and are moved automatically to an open position, as shown by dotted lines in Figure 5 when the device is acting as a stirring structure. A projection 38 is provided on each of the shafts 35, said projections acting as stops for various door sections 34. When shaft 32 is rotating in one direction it acts as a screw and when it is rotating in the opposite direction it acts with the sections 34 as a mixing device. As this shaft carries a sprocket wheel 8, chain 7 may function to rotate the shaft in either direction. As mentioned heretofore, chain 7 is connected with the usual power take-off of a truck and may be operated in either direction, as well as at any time.

What I claim is:—

1. A concrete mixer, comprising a closed tank provided with means acting as an inlet and means acting as an outlet, means for directing water into the tank and a mixing device arranged in the tank, said mixing device comprising a spiral screw and a plurality of gates carried by the screw formed to automatically close when the screw is moved in one direction and to automatically open when the screw is moved in the opposite direction.

2. A concrete mixer, comprising a tank and a mixing structure arranged in the tank, said mixing structure including a shaft, a screw mounted on the shaft, said screw having a plurality of radially-extending openings, a gate arranged adjacent each of the openings and means for pivotally mounting the respective gates and holding them in said positions so that when said shaft is rotated in one direction the gates will line up with the screw and cause the screw formation and when the shaft is rotated in the opposite direction said gates will automatically move to an open position for permitting the matter being mixed to be properly stirred.

3. A concrete mixer, comprising a container and a device arranged in the container for mixing a batch therein, said device including a shaft, a screw mounted on the shaft, said screw having a number of gateways therein, a door section for each gateway, each of said door sections overlapping at each edge portion of the screw when the door section is closed, a radially-extending shaft for each

of said door sections, said radially-extending shafts being rigidly secured to the first-mentioned shaft, means carried by the door sections loosely surrounding said radially-extending shafts, and a stop on each of the 5 radially-extending shafts for limiting the swinging movement of the door sections around the radially-extending shafts.

4. In a concrete mixer, a mixing structure 10 comprising a rotatable shaft, a screw secured to said shaft, said screw having a plurality of gateways, a radially-extending shaft for each of said gateways, said shafts being positioned substantially centrally of the gateways, a door section pivotally mounted on 15 each of said radially-extending shafts, said door sections being formed to close the gateways when moved to a certain position, and a stop on each of said radially-extending 20 shafts for limiting the rotary movement of the door sections.

Signed at New York in the county of New York and State of New York this 28th day of November A. D. 1928.
